Humbert O. Martin,
INVENTOR

BY *Victor J. Evans*

ATTORNEY

WITNESS: *Fred. W. Ely*

UNITED STATES PATENT OFFICE.

HUMBERT OSWALD MARTIN, OF NEW YORK, N. Y.

HAT-CROWN FORMER.

Application filed July 22, 1922. Serial No. 576,797.

To all whom it may concern:

Be it known that I, HUMBERT O. MARTIN, a citizen of the United States, residing at New York city, in the county of New York 5 and State of New York, have invented new and useful Improvements in Hat-Crown Formers, of which the following is a specification.

This invention relates to improvements 10 in devices for forming a bell-crown of a hat, the primary object being to provide a device that will eliminate the possibility of pinching the crown of the hat during the crown forming operation, thereby giving 15 the crown a smooth and neat appearance.

Another object of the invention is the provision of a device which greatly increases the production of hat crowns and is very easy of operation.

With these and other objects in view, the invention resides in novel construction and arrangement of parts, the essential features of which are hereinafter fully described, are particularly pointed out in the appended 25 claims, and are illustrated in the accompanying drawing, in which:—

Figure 1 is a top plan view of the device showing the same applied to a bell-crown die, the device being shown in clamping position.

Figure 2 is a view similar to Figure 1, showing the device in open position.

Figure 3 is a vertical sectional view on the line 3—3 of Figure 1.

Figure 4 is a plan view showing a modified form of the device.

Heretofore machines of this type have been unable to form bell-crowns for hats and at the same time produce a crown 40 which is smooth and free from wrinkles. The device about to be described is capable of overcoming this objection.

Referring more particularly to the drawing, the numeral 5 designates the stand or 45 support for a bell-crown die 6 to which my invention is shown applied. My device comprises a clamping ring as shown at 7 and when in clamping position the inner contour of the ring forms a shape similar to 50 the bell-crown die 6. The clamping ring 7 comprises two sections 8 and 9. The section 9 is divided into two parts 10 and 11 having pivotal connection with each other as at 12. The ends of the section 8 are cut- 55 away as at 13 and the ends of the parts 11

and 12 are likewise cut-away as at 14 so as to produce a smooth joint when the device is in clamping engagement with the crown die as shown in Figure 1 of the drawing. Each section 8 and 9 is capable of movement over the base A of the device and with relation to the crown die 6 by means of cam levers 15 and 16 pivoted as at 17 and 18 to the base A. The cam lever 15 is formed with a circumferential flange 16' for engagement with a pin 17' carried by the section 8. The section 8 is further provided with rails 19 capable of sliding in guides 20 secured to the base A. It will be seen that by movement of the cam lever 15 section 8 70 may be moved either back or forth with relation to the crown die.

Cam lever 16 has link connections 21 with the parts 11 and 12 of the section 9, whereby upon movement of the cam lever 16 the 75 parts 11 and 12 may be swung about their pivot as shown in Figure 2 in the drawings. A slot 22 in the base A receives the lower end of the pivot bolt 23 and allows for movement of the section 9.

In operation the cam lever 16 is first operated to bring the section 9 into clamping engagement with the crown die 6. This having been done the lever 15 is operated to move the section 8 into clamping engagement with the crown die 7 thereby forming a complete ring with a smooth joint between the said sections 8 and 9. For removing the hat after the crown has been formed the operation is just the reverse from that described. It will be seen that the several parts in such manner as to eliminate the possibility of a hat crown becoming wrinkled or creased when the two sections of the clamping ring are brought into clamping engagement. The base A is provided with diametrically apposed openings 29 for attaching the device to a hat machine.

In Figure 4 of the drawings has been shown a slightly modified form of the device. The construction is very similar to the preferred form and consists of rods 24 carried by the section 8. Wound about the rods 24 are coil springs 25, one end of said spring abuts a bearing 26 the other end 100 abutting the head formed on the rod 24. A cam lever 27 is pivoted as at 28 to the base and co-acts with the outer wall of the section 8 for moving the same with relation to the crown die. By this arrangement it is 105 110

seen that the springs will tend to force the section 8 away from the section 9 upon the manipulation of the lever 27.

In the foregoing it will be seen that there has been shown and described a preferred form and a modified form of my invention, and I wish it to be understood that changes, alterations and modifications as come within the claims can be resorted to when so desired.

What is claimed as new is:—

1. In a device of the class described comprising a bell crown die, a base adapted to be arranged adjacent the bell crown die, a clamping ring formed of a pair of sections, guideways for slidably mounting one of said sections on said base, manipulative means for sliding said section including a cam lever, the other of said sections including two parts pivotally connected together and capable of sliding movement over said base, and manipulative means for swinging said parts about their pivots away from said bell crown die, said means including a cam lever.

2. In a device of the class described comprising a bell crown die, a base adapted to be arranged adjacent the bell crown die, a clamping ring formed of a pair of sections, means for slidably mounting one of said sections on said base comprising guideways mounted on said base, and rails carried by said section for co-action with said

guide ways, manipulative means for sliding said section, the other of said sections including two parts pivotally connected together and capable of sliding movement over said base, and manipulative means for swinging said parts about their pivots away from said bell crown die, co-acting portions formed on the ends of the said first mentioned section and on the pivoted parts for preventing wrinkling of the crown of the hat when the sections are in clamping engagement with the same.

3. In a device of the class described, the combination of a bell crown die, a clamping ring therefor comprising a base, a pair of sections, one of which is slidably mounted over said base with relation to said bell crown die, manipulative means for sliding said section including a cam lever pivoted on said base and co-active with said section, the other of said sections constituting a pair of pivoted parts, and manipulative means for swinging said parts with relation to said bell crown die, including a cam lever and links connecting said lever with said parts, co-acting portions formed on the ends of the said first mentioned section and on the pivoted parts for preventing wrinkling of the crown of the hat when the sections are in clamping engagement with the same.

In testimony whereof I have affixed my signature.

HUMBERT OSWALD MARTIN.
